ELECTRODE STRUCTURE FOR TRANSMIT-RECEIVE SWITCHING DEVICES

Henry J. McCarthy, Danvers, Mass., assignor to Bemac Laboratories Inc., Beverly, Mass., a corporation of Massachusetts

Application June 1, 1954, Serial No. 433,477

2 Claims. (Cl. 315—41)

The present invention relates to gaseous discharge switching devices of the transmit-receive type, and more particularly to improved ignitor electrode structure for such devices.

Transmit-receive (TR) switching devices are employed in radio direction and ranging systems to permit the use of a common antenna for both transmission and receiving of radio frequency energy. During transmission of the high power pulse such switching devices decouple the sensitive receiving apparatus by means of ionization of a suitable gas filling under reduced pressure contained within the envelope. The position of the TR switch in the circuit permits essentially all of the transmitted energy to be directed to the antenna. The reflected radio frequency signals will be received by the same antenna and are at too low a power level to cause ionization of the gas filling. Such signals will be permitted to pass through the TR switch to the receiver.

An auxiliary electrode is commonly employed in the TR switch to provide a source of electrons to aid in the ionization of the gas mixture within the envelope. Such electrodes are now referred to in the art as the "keep-alive" or "ignitor" electrode. Their operation, as well as a detailed description of various embodiments, is noted in the text, "Microwave Duplexers," by L. D. Smullin and C. G. Montgomery, McGraw-Hill Book Company, Inc., New York, 1948, pages 199-211 inclusive.

Briefly, the prior art electrodes comprise a core of a conductive metal, such as "Kovar," a nickel-iron-cobalt alloy, surrounded by an insulating sheath over a major portion of its length and exposing only the tip surface. The electrode is introduced into the TR switch tube through an axial passage in a discharge gap conical electrode and is supported by the outer envelope. A direct current sustained glow discharge is maintained in the region extending from the tip area by biasing the ignitor electrode negatively with respect to the adjacent conical discharge gap electrode. Since the direct current glow discharge is continuous, the tip area of the electrode is subject to surface pitting and formation of metallic deposits due to electron bombardment. These deposits gradually reduce the exposed electrode tip surface and will result in momentary glow to arc transitions which cause extinguishing of the ignitor electrode action. Without partial ionization in the discharge gap larger values of radio frequency power will be permitted to pass through the TR switch before a gaseous discharge is initiated. This additional power may exceed the tolerable limits of the receiving apparatus and cause damage to the semiconductor devices employed in such apparatus.

A further difficulty experienced with prior art electrodes during operation is the change in the voltage potential required to initiate the direct current discharge. Build up of the metallic deposits on the tip surface area will result in a higher voltage potential necessary to maintain the direct current glow discharge. Since the auxiliary direct current voltage supply for the ignitor electrode must be designed around specific current limits when in-

2

corporated in a radar system any change in the characteristics of the emitting surface will result in a corresponding reduced current to the point where the ignitor discharge will be extinguished. The term "voltage drop" as commonly employed in the art to refer to the phenomena which occurs in ignitor electrode characteristics during tube life is defined for the purposes of this description as the difference in potential between the ignitor electrode and adjacent discharge gap electrode when the ignitor current has reached the value specified. Any increase in voltage drop will mean a drop in current with a fixed voltage supply.

The mixture of gases now employed in the TR switch tube has been experimentally determined in the art to require a small percentage of water vapor as a necessary component. The presence of this component has created a problem of tube life in such tubes employing the ignitor electrode since the oxygen in the gas filling hastens the formation of metallic oxide deposits on the electrode tip. Prevention of momentary glow to arc transitions or sudden increase of voltage drop above predetermined limits is, therefore, a major aim of the electronics tube industry.

In the process of conducting investigations into various solutions to this problem, I have discovered that the formation of a tenacious semi-conductive protective layer over the exposed ignitor electrode tip successfully protects the electron emitting surface and virtually eliminates the disadvantages of prior art electrodes. Further, since the protective layer has a relatively high electrical resistance, it provides for the formation of a uniform spread of the direct current glow discharge, and also prevents momentary extinguishing of the ignitor action due to glow to arc transitions. While the exact chemical composition of the protective semiconductive layer cannot be accurately determined because of the very small dimensions, the method of fabricating this layer indicates that various oxides of the base metal of the electrode, as well as some oxides of the sheathing material, are present.

It is, therefore, an object of the present invention to provide an improved ignitor electrode for gaseous discharge switching devices.

It is a further object to provide an improved electrode for partially ionizing a gaseous mixture in a transmit receive switching tube, said electrode providing longer tube life by eliminating glow to arc transitions and increases in the voltage drop above tolerable limits.

Other objects, advantages and features of the present invention will be evident after consideration of the following detailed description and reference to the accompanying drawings, in which:

Fig. 1 is a vertical cross sectional view of the illustrative embodiment;

Fig. 2 is an enlarged cross sectional view of a portion of prior art ignitor electrode structure;

Fig. 3 is an enlarged cross sectional view of the improved ignitor electrode of my invention;

Fig. 4 is an enlarged cross sectional view of an alternative embodiment of the present invention; and

Fig. 5 is a curve illustrating performance results during life.

As shown in the drawings, Fig. 1 illustrates a transmit-receive switching device 1, referred to in the art as an integral cavity type. The outer envelope comprises a metallic body member 2 of a general cylindrical cross section with an axial passage therethrough defining wall 3. Spaced within the axial passage and secured to wall 3 are a pair of opposed conical discharge gap electrodes 4 and 5 having their large ends spaced apart to define therebetween resonant cavity 6. The oppositely disposed convergent ends of electrodes 4 and 5 define therebetween discharge gap 7. Axial adjustment of the gap spacing

to the frequency of operation may be made by deforming the flexible diaphragm end of electrode 5 with suitable differential screw mechanism positioned within housing 8.

An exhaust tubulation 9 extends into body member 2 to communicate with the resonant cavity 6 and is utilized for evacuation, as well as filling with the gas mixture under reduced atmospheric pressure.

Positioned at one end of axial passage is a reservoir plug 10 with an annular cup 11 sealed thereto. A reservoir glass bulb 12 is sealed to cup 11 to form a storage chamber for the gas filling.

The ignitor electrode 13 which forms the subject of my invention comprises a core of a conductive metal which is supported at one end by means of a glass to metal seal 14 to the reservoir bulb 12. Electrical contact to a direct current voltage supply and external circuitry may be made by means of top cap 15 sealed to the outer end of electrode 13. The inner tip of said electrode extends axially within the device through a hollow passage 16 in conical gap electrode 4 to a point a critically short distance from the apex of said electrode. An insulating sheath 17 of a dielectric material surrounds electrode 13 over a major portion of its length to prevent arcing to the walls of hollow passage 16.

Prior art electrodes, as well as the improvement disclosed in this specification, will now be described by referring to Figs. 2 and 3. The general construction of the ignitor electrode comprises a dielectric sheath 17 extending to the tip of electrode 13 leaving only the tip surface area 13A exposed. Electron emission is, therefore, directed from this surface area in a continuous stream toward the discharge gap. Surface pitting of the tip and sputtering of metallic deposits onto the sheath 17, as well as tip surface, tends to restrict the emissive area. Momentary glow to arc transitions may occur from these metallic deposits to adjacent cone structure.

According to the teachings of the invention, I envelope the tip surface area with a spherical semiconductive oxide layer 18. This not only protects the emitting surface, but assures the spread of the glow discharge uniformly over the entire spherical oxide surface. The composition of this semiconductive layer will be better appreciated after consideration of the method of manufacture.

I first provide a lead wire of a conductive metal such as "Kovar", an alloy containing approximately 29% nickel, 17% cobalt, 0.3% manganese and the remainder iron, and having a diameter of approximately forty thousandths (.040) of an inch and tapering slightly to a tip diameter of approximately twenty-five thousandths (.025) of an inch. To sheath this wire, an approximate beading glass having a wall thickness of approximately 25 mils (.025) of an inch, such as Corning 7052 glass, is sealed over a major portion of the length by conventional sealing techniques. The tip surface is then ground, etched or sanded to expose the base metal. Next, the tip area is heated with a controlled oxygen-gas fire until the metal begins to oxide rapidly between approximately 1100° C. and the melting point of approximately 1450° C. By rotating while heating, a spherical oxide central layer is formed. The oxide layer thickness is approximately from three (.003) to five (.005) thousandths of an inch and the diameter is between thirty (.030) and thirty-seven (.037) thousandths of an inch.

The oxide protective layer must be dense, adherent and show no ruptures, cracks, pin holes or distortions.

The chemical composition appears to consist essentially of nickel, cobalt and iron oxides with some glass oxides also present. Due to the small dimensions of the completed spherical oxide layer, accurate chemical analysis of the relative percentages of oxides present has been impossible. It is, however, the resultant structure, as well as the method of manufacture, that has contributed to the results obtained without the addition of any other chemicals.

An alternative embodiment as shown in Fig. 4 com-

prises terminating the insulating sheath 17 at a point 19 approximately fifty thousandths (.050) of an inch or less from the tip. The spherical oxide layer 20 may then be formed according to the same steps previously described.

5 In this embodiment there will be no fusing of the glass and metal oxides.

After preparation of the oxide ball tip ignitor electrode it is assembled in the complete device as shown in Fig. 1.

The electrical characteristics of the improved ignitor 10 electrode may be appreciated in Fig. 5. Since certain specified limits must be met according to rigid government inspection standards, I have indicated the lower and upper voltage drop limits for tubes of the type shown in Fig. 1. These limits are respectively 325 to 450 volts.

15 Tubes exceeding these limits during operation will result in erratic performance and, if continued high readings are noted, it means a replacement is in order to assure satisfactory operation. The tubes employing standard ignitor electrode structure have been observed to rise 20 initially, but then to fluctuate fairly close to the upper limit until approximately 700 hours of life when they would rise steadily as shown by curve 21.

Tubes employing the improved ignitor electrode have demonstrated a much desired stability during life up to

25 1000 hours and have stayed comfortably within the specified limits. Curve 22 illustrates these results which can be attributed primarily to protection against electrode surface deterioration, as well as the providing of a high resistance immediately at the tip area which will result

30 in very fine current paths all around the spherical protective layer rather than a concentration at one particular point. This dispersion of current paths results in a uniform direct current glow discharge all around the oxide sphere. Another advantage of the improved structure is to aid in the elimination of any relaxation oscillations of the discharge mentioned on pages 201-206 of the aforementioned reference. It has been noted in the prior

35 art that such oscillations can be eliminated by placing a high resistance directly at the TR switch tube, see Patent No. 2,582,202 issued January 8, 1952, to Carlyle W. Jacob.

It is the practice in the art to incorporate a resistance in the order of one half megohm close to the top cap connection 15 in Fig. 1. My invention places additional high resistance at its most effective position to 40 eliminate reflex oscillations, namely, at the tip surface. Ohmic values of approximately 10,000 ohms have been measured for the spherical oxide protective layer.

There has thus been described an embodiment of an improved ignitor electrode structure which may be 45 incorporated in all modifications of transmit-receive switches. Another embodiment to which the present invention is applicable is referred to as the band pass type and is illustrated in a disclosure Serial No. 299,895, filed July 19, 1952, by Harold C. Booth, now Patent No. 55 2,680,207 assigned to the same assignee as the present application.

What is claimed is:

1. In a transmit-receive gaseous discharge switching device having a resonant cavity and plural spaced conical electrodes axially disposed therein defining a discharge gap, an ignitor electrode extending axially into one of said discharge gap electrodes comprising a core of a conductive metal, a sheath of an insulating material covering a major portion of the lateral surfaces of said core and exposing only the tip area, a substantially spherical layer of a non-emissive high resistance material surrounding the exposed tip area, said spherical layer being composed of oxides of said conductive core and insulating sheath without any additives.

60 2. In a transmit-receive gaseous discharge switching device having a resonant cavity and plural spaced conical electrodes axially disposed therein defining a discharge gap, an ignitor electrode extending axially into one of said discharge gap electrodes comprising a core of a conductive metal, a sheath of an insulating material covering

75

a major portion of the lateral surfaces of said core and terminating a short distance from the tip area of said core, a substantially spherical layer of a non-emissive high resistance material surrounding the tip area of said core, said spherical layer being composed of metallic 5 oxides of said conductive core without any additives.
